ROOF JACK

Kenneth S. Jenson and Willis N. Nelson, Wisconsin Rapids, Wis., assignors to Preway Inc., Wisconsin Rapids, Wis., a corporation of Wisconsin

Application October 23, 1951, Serial No. 252,630

3 Claims. (Cl. 98—46)

This invention relates to a roof jack designed for application to an inclined roof. It incorporates in its structure a flashing-collar unit which may be affixed to a roof having a pitch within the normal range of building structures. In such an assembly the collar provides a mounting whereon a smoke pipe may be maintained vertically with full weather protection thereto at the point where it emerges through the roof.

A roof jack of this kind may be produced economically from sheet metal with but few parts. When installed and properly adjusted, a lock is applied to make the adjustment permanent. Thereafter the smoke pipe will be supported vertically in spaced relation to the roof and also to the ceiling therebelow, but with ample provision for ventilation at these points.

A suggestive embodiment of this invention is illustrated in the accompanying drawing wherein—

Figure 1 is a perspective view of the roof jack as it appears when operatively installed, portions of the roof jack and its associated roof and ceiling being broken away to better exhibit the construction;

Fig. 2 is a central vertical section through the installed roof jack and surrounding roof structure; and

Fig. 3 is a transverse section, taken on line 3—3 of Fig. 2.

In the drawing a conventional roof R is shown of normal pitch spaced from a horizontal ceiling 6 therebelow. The supports for the roof and ceiling are unimportant to this invention, consequently are not illustrated. Suffice to say that an opening is formed through the ceiling in register with a similar opening in the roof thereabove for the reception therethrough of a vertical smoke pipe P. This pipe occupies a more or less central position within the two openings so as to remain spaced from the ceiling and roof of the building structure.

A pipe shield S comprising upper and lower sections 10 and 11 surrounds the smoke pipe between the ceiling 6 and the roof R. These sections are telescopically interfitted so as to be extensible or contractible according to the distance between the ceiling and the roof at the point of installation. The lower shield section 11 is formed with spaced rows of circumferentially spaced tongues 14 and 15, respectively, adapted to embrace the top and bottom sides of the ceiling to fix the position of the shield. This lower section of the shield is also provided along its bottom with an downturned flange 16 which is extended continuously through 360° to produce a finished trim at this point.

The upper shield section 10 is cut at the time of installation to correspond to the pitch of the roof. Slits are then cut so that a series of tabs 10a and 10b are formed around its perimeter. The tabs 10b stop against the bottom side of the roof and the tabs 10a are bent down against the top side of the roof to hold the shield 10 in place.

An escutcheon 18 which is fitted into the lower section of the shield is provided with ports 19 which are adapted to be closed or opened in varying degree by an annular damper plate 20 that is mounted for rotation thereon. A finger piece 21 which depends from this damper plate passes through an arcuate slot in the escutcheon to provide a ready means for operating the damper to a desired rotative position.

The smoke pipe P in its lower end portion is operatively connected to a flue pipe 23 leading from a space heater or heating plant within the building. At a point close to its upper end the flue pipe 23 is engaged by the

escutcheon 18, the latter thereby affording lateral support to the flue pipe and to the smoke pipe P in connection therewith. In the upper portion of the smoke pipe a sleeve 24 is closely fitted thereupon to constitute an extension therefor. Bracket arms 25 upstand from the upper end of the sleeve to support a bonnet 26. The vertical position of the sleeve-bonnet-smoke pipe assembly is fixed by means shortly to be described.

A collar C is formed to receive the smoke pipe P therethrough. This collar is elongated with opposite side walls 28 that are substantially flat. A base for the collar is provided by a flashing plate 30 which is lock-seamed thereto and extended therefrom to overlie the adjacent portions of the roof to establish a weather-tight connection therewith. The collar supports at its top an elongated insect screen 31 whose sides are downturned at 32 to partially lap the elongated side walls of the collar C. The screen which is centrally apertured to receive the smoke pipe therethrough is free to shift its position longitudinally upon the collar, as required by the latter's inclined position upon the roof where installation is made.

A hood H is carried by the smoke pipe extension 24 to whose bottom end portion it is lock-seamed at 35. This hood is formed with opposite arcuate end portions 36 and 37 interconnected by elongated vertical walls 38 which lie just to the outside of the flat elongated walls 28 of the collar. A pin 40 traverses the hood, collar, and smoke pipe to establish therebetween an adjustable pivotal connection. The vertical position of the sleeve-bonnet assembly is fixed, and the same is true of the smoke pipe P.

When the roof jack is in process of being installed, the collar-flashing assembly is first secured in place, the angle of its inclination being determined by that of the roof. The smoke pipe P having the sleeve 24 and the hood H secured thereto is manipulated to a vertical position, passed through the collar C and then connected to the flue pipe 23. The pin 40 is then passed through the hood, collar and smoke pipe and the hood is secured to the collar by lock straps or wires 41 which are tied to opposite ends of the hood H at its base and to the proximate end of the collar C near its top. Each strap extends between an end of the hood and the proximate end of the collar. These straps or wires may conveniently be made of metal and slots 41a for their reception are preformed in the hood and collar to facilitate their application. The strap ends are inserted through the slots and then bent around them. When done, the hood ends will be extended beyond the ends of the collar C and below its upper portion to provide adequate weather protection therefor.

It will be noted that one arcuate end portion of the hood is somewhat larger than the other so that the interconnecting walls 38 are non-symmetrical. In the construction illustrated, this inclination is not parallel with the roof, but its divergency, such as it is, is unimportant since there is sufficient overhang at opposite ends of the hood to afford ample weather protection to the collar and interior of the pipe shield.

An important feature of this roof jack is its adaptability to roofs of varying pitch. No account need be taken of the exact inclination in any case since the hood-smoke pipe assembly is readily adjustable to meet varying conditions. As a result, a single model of hood-collar assembly will suffice for installations where the roof pitch conditions are widely divergent.

We claim:

1. For mounting upon an inclined roof having an opening through which is extended a vertical, cylindrical smoke pipe, a roof jack comprising an elongated collar having a flashing plate secured to the lower end of the collar and extending over the opening in the roof fixedly secured to the roof, said collar upstanding from the base in surrounding relation to the smoke pipe and having flat sides and rounded ends, a cylindrical sleeve surrounding the smoke pipe in its upper portion, an inverted hollow hood secured to the sleeve at a point above the collar and depending from the sleeve and formed with opposite flat sides and arcuate ends lapping opposite flat sides and ends of the collar, a transversely extending pin extending through the hood, collar, and smoke pipe

mounting the collar for pivotal movement with respect to the hood and smoke pipe whereby to free the collar for inclined positioning on the roof in accordance with the pitch thereof when the smoke pipe is disposed in a vertical position, and removable straps fastened to the upper edge of the collar and extending downwardly between the hood and the collar and adapted to be secured to the lower edge of the hood when the hood and smoke pipe are adjusted to the pitch of the roof to maintain the smoke pipe in vertical position, said straps being located within the sheltered area provided by the hood.

2. For mounting upon an inclined roof disposed above a ceiling and having an opening through which is extended a vertical smoke pipe, a roof jack comprising a shield for the portion of the smoke pipe between the roof and ceiling including a pair of telescoping cylindrical sections secured to the roof and ceiling respectively, an elongated collar having a flashing plate extending over the opening in the roof fixedly secured to the roof, said collar upstanding from the base in surrounding relation to the smoke pipe and having flat sides and rounded ends, the opposite long flat sides of the collar being disposed in the direction of the inclination of the roof, a hood extending around and fixedly carried by the smoke pipe at a point above the collar and formed with opposite elongated sides lapping the opposite elongated flat sides of the collar, the ends of the hood being curved downwardly to extend beyond the collar ends in lapping relation thereto but spaced therefrom sufficiently to be clear thereof in various adjusted positions of the hood relative to the collar, a pin extending between the collar, hood and smoke pipe providing a pivotal connection therebetween whereby to free the collar for inclined positioning on the roof in accordance with the pitch thereof when the smoke pipe is disposed in a vertical position, and removable strap means adapted to be extended between and secured to the ends of the collar and the ends of the hood within the confines of the hood for fixedly locking the hood to the collar when the hood is adjusted to the pitch of the roof whereby to maintain the smoke pipe in vertical position.

3. For mounting upon an inclined roof having an opening through which is extended a vertical smoke pipe,

a roof jack comprising an elongated collar having a base fixedly secured to the roof and flat sides and ends upstanding therefrom in surrounding relation to the smoke pipe, an inverted hollow hood fitted around and fixedly carried by the smoke pipe and formed with opposite elongated sides lapping the opposite elongated flat sides of the collar, a pin extending through the hood, collar and smoke pipe establishing a pivotal connection between the hood and the collar to free the collar for inclined positioning on the roof in accordance with the pitch thereof when the smoke pipe is disposed in a vertical position, a screen panel extended over the top of the collar and having means defining a vertical opening for reception of the smoke pipe, said screen panel being longer than the length of the sides of the collar to enable adjustment of the screen panel on the collar without uncovering the collar, downturned sides on the screen engaging the sides of the collar to provide a guide for the screen panel to permit sliding movement thereof only in a direction lengthwise of the collar whereby to be self-adjusting according to the rotative position of the collar relative to the smoke pipe, and straps extending between and secured to the hood and collar fixedly locking the hood to the collar whereby to maintain the smoke pipe in vertical position.
